UNITED STATES PATENT OFFICE

ELMER S. STACK, OF SOMERVILLE, MASSACHUSETTS

COMPOUND WATER HEATER

Application filed January 22, 1927. Serial No. 162,763.

The present invention relates to apparatus for heating water, and has for its object to provide means by which water contained in different pipe systems or tanks may be heated in the same heating unit with circulation of water in each system and without drain upon, or interference with the circulation of water in either system when water is drawn from the other system. The invention is preferably embodied in a single unit piece of apparatus which, for convenience of description, I call a heater, and have entitled, for the purposes of this specification, a "compound water heater". The preferred structural characteristics of the invention are shown in two embodiments and in connection with different heating systems illustrating some of the possible uses thereof, in the accompanying drawings, and are explained in the following specification.

In the drawings,

Fig. 1 is a longitudinal central section of one form of heater embodying the invention;

Figs. 2 and 3 are cross sectional views on the lines 2-2 and 3-3, respectively, of Fig. 1;

Fig. 4 is a diagrammatic view illustrating the use of said heater, in connection with a storage tank in a domestic hot water supply system, for heating and maintaining circulation of the water in such tank and supply system;

Fig. 5 is a view similar to Fig. 1 showing a modified form of heater unit adapted to heat and circulate water in a number of separate hot water supply systems;

Fig. 6 is a diagram illustrating the use of the heater shown in Fig. 5 in connection with two hot water supply systems;

Fig. 7 is a similar view illustrating the same heater used both to furnish a supply of hot water for washing and like purposes, and to circulate hot water for heating purposes.

Like reference characters designate the same parts wherever they occur in all the figures.

Referring first to the heater shown in Figs. 1-4 inclusive, this apparatus comprises an outer shell 11 with which are united integral-
ly or separately as desired, end walls or tube

sheets 12 and 13. This structure may be made as a single integral casting, if desired, and is preferably provided with flanges or lugs 14 and 15 for connection of separable heads or fittings 16 and 17.

Extending between the tube sheets 12 and 13 are tubes 18, for conveying the water in course of being heated, the ends of which pass into holes in the tube sheets and are made fast therein. These tubes are preferably somewhat bent between their ends in order to accommodate themselves to unequal expansion and contraction of the shell, due to temperature changes, without slipping or working loose at their points of connection with the tube sheets. Any desired number of such tubes may be provided in the heating unit, having regard to the size of the shell and the proper size of the tubes to be used. Pipes 19 and 20 are connected to the side of the shell to conduct into the space therein around the tubes 18 the heating fluid, which may be hot water or steam from the boiler or furnace of a hot water or steam heating system, or other heating agent.

The head 16 is provided with a flange 21 for attachment to the flange 14 by bolts 22 or the like; and with an annular rib 23 adapted to bear on the tube sheet, or on a gasket laid thereon, in a circuit surrounding the area in which the adjacent ends of the tubes are located. This head is recessed to provide an internal chamber 24. Connected to the head at one side of a diametral or medial plane of the unit is an ejection pipe 85 for leading away the heated water.

The opposite head 17 is of generally similar character, with a flange 26, to receive the connecting bolts 27, an annular rib 28, and internal space or recess. But it has in addition an intermediate partition 29 dividing its interior space into two chambers 30 and 31. Two pipes 32 and 33, respectively, are connected with the head 17, one of them opening into each chamber. The head is preferably made as a metal casting having holes at one side to receive the pipes 32 and 33, and having the partition formed as an integral rib extending between the holes. Preferably the edge of this rib lies in the same plane with 100

the annular rib 28 so that it bears against the tube sheet 13 or the packing gasket 34 laid against the tube sheet, when the head 17 is applied to the shell. Thus the two chambers in the head are then entirely shut off from one another. The partition 29 is so disposed with reference to the tubes 18 that a part of said tubes opens exclusively into one of the chambers, and another part of the tubes 10 opens exclusively into the other chamber. Preferably also the head 17 is so applied to the shell that the pipe connections 32 and 33 are at the opposite side of a diametral or medial plane of the heater from the eduction 15 pipe 25.

It follows from the characteristics of the heater above described that water from different sources may be conducted to the heater through the pipes 32 and 33, respectively, 20 and will flow in parallel courses through different tubes, becoming heated therein, before mingling in the chamber 24. The partition 29 performs an important function in preventing mingling of the water from the different sources, which may be at different temperatures, before passing into the part of the heater where water is heated. This same function and result may be accomplished by means equivalent to the partition 29 of other 25 construction and form, wherefore I do not limit my invention and protection to the illustrated construction exclusively, although I claim such construction as the best means now known to me for accomplishing the desired result. I may observe at this 30 point that my invention is not conditioned on obtaining an absolute and total exclusion of the water in either chamber 30 or 31 from the other, but my main object is accomplished 35 if flow from one chamber to the other is made so difficult that the path of least resistance of the water is into and through the heating tubes. Neither do I limit my invention and protection to a construction in which the 40 number of channels and chambers for conduction and reception of incoming water is two only, for it is within my contemplation 45 to provide for a further subdivision into three or more chambers or channels.

The arrangement of the inlet pipes 32, 33, and the outlet pipe 25, on opposite sides of a diametral plane is a feature of advantage, for which I claim protection, because it enables the heater to be used in a substantially 50 horizontal position, with the inlet pipes at the lower side, as well as in the upright position here shown.

I have shown in these drawings gaskets 34 between the shell and both heads. These gaskets not only seal the joints between the heads of the shell, but they have a further important function in preventing galvanic action between the tubes and the tube sheets when these are of different metals, by excluding 55 water from contact with the outer surfaces of

the tube sheets. Commonly, in heaters of this character, the shell, including the end walls or tube sheets, is made of cast iron, and the tubes are of copper or brass. The gaskets surround the ends of the tubes closely 60 in leakage tight contact therewith. Thus the water which fills the chambers within the heads is prevented from coming into contact with the portions of the shell (that is, the end walls or tube sheets) through which the 65 tubes pass, and no opportunity is given for galvanic action, with consequent rapid corrosion of either the tubes or the shell, or both, to occur.

A convenient mode of applying the gaskets 80 and insuring the desired character of closeness between them and the tube ends is to apply them to the outer surfaces of the ends of the shell, or of the tube sheets in case separate plates are provided as tube sheets, before 85 the holes are drilled to receive the tube ends. The gaskets may then be placed in shallow depressions in the tube sheets, as indicated in the drawings, and the holes drilled through both the tube sheets and the gaskets in one 90 operation. The tubes, being then inserted, and their ends expanded in the ordinary way, are brought into the required close and leakage tight contact with the gaskets. Although 95 in the foregoing description I have referred to the gaskets in the plural number, it is to be understood that the description which I have given applies to each gasket and either end of the shell, and to each tube which is thus 100 combined with a gasket.

I may use, for the purposes of such gaskets as I here describe, sheets of lead or copper or other material. In this connection lead typifies a material which is inert to galvanic action in the circumstances here considered, and copper typifies material which is so similar to the material of which the tubes are made in its electrochemical nature, that no galvanic electrical action between it and the tubes will take place in contact with water containing in solution the salts, etc. which cause such action to take place between dissimilar metals.

It should be noted, however, that this feature of the invention is not limited to the provision of separate gaskets or plates as the means for preventing the action which causes rapid corrosion in these circumstances, for I may also secure immunity in this particular by other means, as, for instance, by plating or otherwise coating the outer faces of the tube sheets with copper or some other material which will give immunity from the objectionable action.

The form of heater just described lends itself to use in a system such as shown in Fig. 4, to maintain circulation of hot water throughout the pipe line which conveys hot water to the places of use. While this system was not first invented by me, but is the 125 130

invention of Neils M. Knudsen of Portland, Maine, patented in Patent No. 1,730,736, October 8, 1929, I will describe it briefly as illustrating one of the important uses to which my improved heating unit is adapted. The heater and its visible parts and connections are designated by the same characters previously used. The means for supplying heat is typified by the furnace or boiler 36 of a steam or hot water system, to the water space of which the pipes 19 and 20 are connected. 37 is a storage tank to the upper part of which the eduction pipe 25 leads, and from the lower part of which the pipe 32 leads to the heater. The hot water supply pipe 38 issues from the top of the storage tank and is coupled to a pipe 39 which typifies a supply pipe or system of pipes leading to the various places where hot water is to be supplied and from which there are branches 40, 41, etc., to the various hot water faucets or other outlets. A return pipe 42 is connected by a pipe 43 with the induction pipe 33. So long as heat is supplied by the boiler water to the water heater, a circulation is maintained not only in the circuit formed by the storage tank, the heater 11, and the pipe connections 25 and 32, but also in the longer circuit made by the heater, eduction pipe 25, pipe system 38, 39, 42, 43, and the separate channel in the head 17 to which the induction pipe 33 leads. Such a circulation is insured by the partition 29 or its equivalent which compels all the water entering the heater to flow into the heating tubes, where it is heated and caused to rise, and prevents or hinders flow of cold water from the lower part of the tank and pipe 32 into the pipe 33. In the absence of the partition a reversed flow of water upon opening a faucet, might occur through pipes 32, 33 and 43 from the lower levels of the tank, particularly when the opened faucet is so located that the path to it is shorter in this direction; but with the partition, flow to an opened faucet can take place only in the direction of the prescribed circulation. Such circulation keeps the water hot up to all the points from which the branches 40, 41, etc. lead to the several faucets.

Referring now to the heater or unit shown in Fig. 5, this is like the one first described, in substance, in all but the following particulars. First, the head 16^a, unlike the head 16, but like the head 17, is divided by an interior partition 44 into two chambers 45 and 46, and there are two eduction pipes 25^a and 25^b coupled to the head and opening into the respective chambers. This head is applied to the heater shell in such a way that those heating pipes which open into the chamber 30 lead also into the chamber 46, and those which open into the chamber 31 lead to the chamber 45. Thus there is not only a separation between water entering the heater from different sources, but a like separation is

maintained as to the water leaving it. This heater therefore is adapted to serve such a use as that shown in Fig. 6, where separate supplies of circulating hot water are furnished for different apartments. The storage tank 47 and the conducting system associated therewith, for one apartment, are connected by pipes 48 and 49 with the eduction pipe 25^a and induction pipe 32 of the heater; while the storage tank 50 of another apartment is connected by pipes 51 and 52 with the eduction pipe 25^b and induction pipe 32. While a single heating unit provides hot water for both apartments, the supply systems of the different apartments are separate from one another, and the occupants of each can draw hot water without diminishing the supply available at the same time for the occupants of the other, and without interfering with the normal working of the heater. The water is continuously circulated in each system moreover, at least as far as the storage tank, and a continuous supply of hot water is maintained in each storage tank readily for instant delivery when demanded.

In Fig. 7 the same type of heater is shown as supplying through one of its channels hot water to a storage tank 53 for the same purpose as last stated, and through another channel and pipes 51^a and 52^a to a heating radiator 54 in a garage or other detached building.

It is to be understood in this case also that the flow channels in the heater may be subdivided into more than two as in case separate water supplies are to be heated for more than two apartments, etc., and also that the different channels or flow spaces in the same heater may be of unequal areas or volumes, according to the requirements for heat of each water system. It will also be understood that the pipes leading to the head at one end of the heater may be at the opposite side of a given longitudinal medial plane, from the pipes leading from the head at the opposite end, as shown and described in connection with Fig. 1, wherefore the last described form of heater may also be used in a horizontal position.

An additional feature shown in Fig. 5 is the provision of openings in the opposite sides of the shell in either of which pipes for circulating the heating fluid may be connected. The openings not used for this purpose are stopped by plugs 55. This provision enables the heater to be installed easily in situations where connection with supply or return pipes could not be well made at one particular side, or both at the same side, and also enables connection to be made for circulating heating fluid furnished by two or more different sources at the same time.

What I claim and desire to secure by Letters Patent is:

1. A domestic water heating unit comprising

ing a shell having tube sheets at opposite ends and pipe connections in its sides, conducting tubes fitted and secured at their ends in holes in the respective tube sheets, and heads secured to opposite ends of the shell over the openings to the tubes, one of the heads having a single interior chamber into which all of the tubes open and from which there is a hot water outlet, and the other having an interior transverse partition dividing it into two chambers into each of which different groups of tubes open separately and exclusively and into each of which there is an inlet for water to be heated.

15. 2. A domestic water heating unit for use in a hot water system provided with separate return channels which consists in a shell having inner tube-sheets at opposite ends, tubes extending through the space from one sheet to the other, pipe connections in the side of the shell opening to the space around said tubes and between the tube sheets for a heating agent, and heads at opposite ends of the shell enclosing chambers into 20 which the said tubes open, one of said heads having an outlet for eduction of heated water and the other head having an interior partition dividing it into separate chambers and having separate connections to the different 25 chambers for inlet of water through the separate return channels of the water system.

In testimony whereof I have affixed my signature.
